FABRIC CUTTING, EDGE TRIMMING, AND REWINDING MACHINE

David E. Van Maldeghem, New York, N. Y.

Application July 3, 1944, Serial No. 543,259

4 Claims. (Cl. 164—65)

This invention relates to fabric cutting machines and particularly to a continuous cutting machine forming strips preferably of uniform width such as towels, doilies, scarfs and the like on a continuous production basis.

An object of this invention is to provide a plural rotary knife cutting machine adapted to continuously convert rolls or bolts of fabric into uniform width strips substantially without manual intervention.

Another object of this invention is to provide rotary cutters mounted for slidably adjustable relation from each other so as to sever a roll of fabric intermediate its width and to trim both side edges of the fabric in a single operation.

Another object of this invention is to provide a friction roller mounted at the rear of said table with the upper surface of said roller positioned at the level of the top of said table, the friction roller having a felted peripheral surface adapted for feeding fabric before attachment to a rewinding roller.

Another object of this invention is to provide a drive shaft at the rear of the table and to mount the rotary cutters on arms to swing on the drive shaft to and from the table and to provide means for releasing one or more of the cutters from driving connection and swinging same to inoperative position above the table.

Another object of this invention is to provide a cutting, edge trimming and rewinding machine for fabric having linear dividing lines printed thereon, the said machine comprising a plurality of rotary cutters which may be moved as a unit into alignment with the linear dividing lines on the fabric to secure uniformity in the cutting operations in accordance with the design on the fabric.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a front elevation of the machine, showing a bolt of cloth in operative position, three rotary cutters being in position for cutting the cloth into uniform widths and for trimming the edge portions of the cloth.

Figure 2 is a side view of the machine shown in Figure 1, showing the manner of engaging and smoothing the fabric while passing along a predetermined path on alining rods, and also showing the rewinding roller.

Figure 3 is a top plan view of a cutter-carrying

arm and rotary cutter in assembled relation on an enlarged scale.

Figure 4 is a view, partly in cross section, of a modified pulley mounted on the drive shaft, the pulley being disengageable from the drive shaft.

Figure 5 is a top plan view of mechanism for locking the cutter arms and rotary cutters as a unit.

Figure 6 is a fragmentary view of mechanism for controlling the movements of the fabric guide panels.

Figure 7 is a cross-sectional view of a friction clutch for compensating for variations in diameter of the rewound fabric on the rewinding roller.

Figure 8 is a fragmentary side view of supporting means for the friction roller shaft and for the shaft that drives the rotary cutters.

In the illustrated embodiment of the invention the numeral 10 indicates a plural cloth cutting and rewinding machine, comprising a rectangular frame 11 having a portable platform 12 for supporting a bolt of fabric 13. A horizontal table 14 is fixed to the frame at an elevation above the platform suitable for operating purposes.

At the rear of the frame 11 is an upright extension 15 providing a mounting for a drive shaft 16 for a plurality of rotary cutters 17. A friction roller 18 is rotatably mounted in bearings 20. The friction roller has a felted peripheral surface adapted for feeding fabric in contacting relation therewith by frictional engagement. The upper surface of the friction roller is in line with the top of the table 14.

As best shown in Figure 2, each end of the frame 11 comprises channel-shaped legs 22, arranged to face each other, so as to provide an opening in which is fixed a rectangular panel 23. The panel 23 abuts the lower face of the table 14. Alining rods 24 are fixedly mounted in openings in the panel and pass outwardly therethrough. The alining rods are preferably positioned in rectangularly spaced relation. Substantially at the central portion of the panels 23 are openings serving to receive an enlarged tubular alining rod 25 which is held fixed in the panels.

It is to be noted that the friction roller 18 has a felted friction surface on its outer periphery and that this felted surface is adapted for feeding fabric by frictional engagement.

Fixed to the rear wall of the frame 11 are brackets 26 having arcuate free end portions 27, serving to receive ball bearings 28, through which a roller shaft 29 passes and supports a rewinding roller 30.

It is to be understood that there is a considerable drop for the fabric from the upper surface of the friction roller 18 to the floor or even to the rewinding roller 30 and that the weight of this overhanging material is sufficient to cause

the friction roller to exert a drag on the fabric, whereby the friction roller is able to carry the cloth away from the rotary cutters and this movement of the cloth can take place without the assistance of the rewinding roller 30.

The drive shaft 16 is rotatably mounted in the rear extension 15 above the table 14. Slidably mounted on the drive shaft 16 are arms 31 having rotary cutters 17 rotatably supported in bearings 33 at the free ends of the arms, as shown in Figure 3.

In the embodiment shown, the mid-portion of each arm 31 is slotted to receive a pulley 34 which coacts with a pulley 35, suitably mounted to drive a cutter shaft 36. A belt 37 connects the pulleys 34 and 35 and serves for transmitting power from the drive shaft 16 to the rotary cutters.

Figure 4 shows a modified drive pulley 40 which may be used in place of the pulley 34, for the purpose of providing a means whereby the rotary cutters 17 may be slidable with relation to the drive shaft 16 and be operatively connected with the drive shaft during rotation of said shaft. The pulley 40 is V-shaped at 41 to receive the belt 37. The shaft 16 has a keyway 42 which extends substantially throughout its length.

A radially movable key 43 is mounted in an aperture 44 at the mid-portion of the belt groove in the pulley. At the lower end of the key 43 is a reduced portion 45 which is of a size to be in slidable engagement within the keyway 42.

A spring-pressed locking pin 46 is slidable in the pulley 40 and is designed to selectively enter one of two spaced-apart notches 47. A knurled finger piece 48 fixed to the key 43 and slidable in a vertically positioned clearance slot 49 serves for raising or lowering the key 43 so as to bring the reduced portion 45 of the key in or out of engagement with the keyway 42. A plate 50 suitably secured to the pulley 40 holds the spring-pressed locking pin 46 in tensioned engagement with one of the notches 47.

It is to be noted that by raising the key 43 out of engagement with the drive shaft 16 by means of mechanism heretofore described, it is possible to move any one of the rotary cutters out of cutting position and to an inoperative position shown in dot-and-dash lines in Figure 2, where the cutter arm and cutter rest upon a bar 52 secured to the upright extensions 15 at the rear of the machine.

The cutter-carrying arms 31 are pivotally mounted to swing on the drive shaft 16 to and from the table 14.

As shown in Figure 5, belt guards 53 may be suitably secured to the arms 31 which carry the rotary cutters. A bar 54 passing across the top of the arms and in contact with the belt guards may be fastened to the belt guards by clamps 55 pivotally mounted at 56. The clamps may have arcuate slots 57 in engagement with pins 58 on the belt guards. The mechanism shown in Figure 5 serves for slidably mounting the cutters in spaced relation from each other and to be movable as a unit to and from the table 14 and also movable as a unit lengthwise of the table. By moving the bar 54 all the clamped cutters 17 move in unison and may be caused to follow the linear dividing lines as well as the trimming lines on the fabric as a unit.

It is to be noted that when the clamps 55 are released, the bar 54 may be removed to permit any one of the cutter arms 31 and its attached cutter 17 to be swung rearwardly out of oper-

ative engagement and in inoperative position, resting against the bar 52 shown in Figure 2.

Guide disks 60 are secured to two slidable panels 23' and are slidably mounted with the panels on the alining rods 24. The slidable panels and the attached guide disks are adjustable to and from each other by means of handwheels 61 secured to shafts 62 rotatably mounted in bearings 63 which are fixed to the frame 11.

10 Each handwheel 61 actuates a shaft 62 and a sprocket wheel 64 which is fixed at the far end of the shaft and over which passes a chain 65 supporting a weight 66.

Each chain 65 passes through the tubular alining rod 25 in direction of one of the panels 23'. The free end of each chain is secured to a pin 67 passing through a flange 68, which is suitably fastened to the panel 23'. A coil spring 69 has its opposite ends secured to the pins 67. The pins 67 are slidable in a slot 70 in the lower portion of the tubular alining rod 25, shown in Figure 6.

Elongated sleeves 71 secured to the flanges 68 and freely slidable on the alining tube 25 serve to maintain the panels 23' in vertically alined position.

Each handwheel 61 is adapted to cause slidable movement of a panel 23' and make it possible to adjust the positions of the panels and the guide disks and guide the edge portions of the fabric along a predetermined path.

In order to compensate for the constantly changing diameter of the fabric on the rewinding roller 30, a friction clutch 73 is mounted on the shaft 74 of the friction roller 18. The friction clutch permits slippage of the friction roller 18 when the rewinding roller 30 has fabric wound thereon to a large diameter and the rewinding roller tends to pull more fabric than that fed by the friction roller.

40 The friction clutch 73 comprises a pulley 72 having a friction surface such as leather 75, against which a belt drive idler pulley 76 is urged by a spring 77, as is well known in the art. (Figure 7.)

Operation of invention

The operator places a bolt of fabric 13 on the platform 12. The fabric is passed over the large tubular alining rod 25, under the lower rear alining rod 24', over the top of the upper rear alining rod 24', over the upper front alining rod 24³, under a front alining rod 24⁴, over a lifting block 78 in front of the cutters 17 and extending transversely across the entire table 14. The fabric 13 then passes over the friction roller 18 and is then attached to the rewinding roller 30.

50 A belt 79 on an electric motor 80 drives a transmitter 81, which is well known in the art for at will applying or cutting off power. The transmitter 81, by means of a belt 82 is engaged with a pulley 83 on the drive shaft 16 and transmits power to the drive shaft 16 and to the rotary cutters 17.

55 A further belt 84 drives the pulley 76 on the friction roller 18. A belt mounted on the pulley 12 drives a pulley 86 on the rewinding roller 30.

60 As shown in Figure 1, a sprocket chain 90 has its opposite ends connected to the end carriers 31 of the rotary cutters. The chain 90 passes over upper and lower sets of sprockets 91, mounted 70 in bearings 92 which are fixed to the upright extensions 15 of the frame. A handwheel 93 is secured to a shaft 95 which is fixed to one of the lower sprockets 91. The handwheel 93 serves for moving the sprocket chain 90 and for adjusting 75 the positions of the rotary cutters. The guide

disks 60 engage and guide the opposite side edges of the fabric 13.

It is to be noted that when the fabric is wound on a roll 95, Figure 2, that the fabric is first passed over a lower front alining rod 24⁶ and then under the alining rod 24¹ and over the other alining rods as heretofore described.

In accordance with the patent statutes I have described and illustrated the preferred embodiment of my invention, but it will be understood that various changes and modifications can be made therein without departing from the spirit of the invention as defined by the appended claims.

I claim:

1. In a cloth cutting machine comprising rotary cutters adjustable for shearing textile fabric having spaced linear dividing lines into strips of equal width and in one operation, a portable platform for supporting a roll or bolt of fabric, a frame, a plurality of horizontally supported alining rods positioned in said frame in rectangularly-spaced relation for engaging and smoothing said fabric, a horizontal table, a friction roller having its upper surface in line with the top of said table and being mounted at the rear of said table, said roller having a felted friction surface adapted for feeding said fabric by frictional engagement, a drive shaft mounted above said table, arms slidably mounted on said drive shaft and having rotary cutters supported at the free ends thereof, said drive shaft and said arms having pulleys connected by belts for transmitting power from said drive shaft to said rotary cutters, a power-driven rewinding roller at the rear of said frame, a plurality of guide-disks slidably mounted in sets on opposite sides of said frame for guiding the edge portions of said strip fabric along a predetermined path, said strip fabric passing between said guide-disks, then rearwardly over said table, over said friction roller and being secured to said rewinding roller, said rotary cutters being pivotally mounted on said arms to swing on said drive shaft to and from said table, means for slidably mounting said cutters for adjustment in spaced relation from each other, and means for releasing one or more of said cutters from driving connection and swinging same to inoperative position above said table.

2. In a cloth cutting machine comprising rotary cutters adjustable for shearing textile fabric having spaced linear dividing lines into strips of equal width and in one operation, a portable platform for supporting a roll or bolt of fabric, a frame, a plurality of horizontally supported alining rods secured at opposite ends of said frame and being positioned in rectangularly-spaced relation for engaging and smoothing said fabric, a horizontal table, a friction roller having its upper surface in line with the top of said table and being mounted at the rear of said table, said roller having a felted friction surface adapted for feeding said fabric by frictional engagement, a drive shaft mounted above said table, arms slidably mounted on said drive shaft and having rotary cutters supported at the free ends thereof, said drive shaft and said arms having pulleys connected by belts for transmitting power from said drive shaft to said rotary cutters, a power-driven rewinding roller at the rear of said frame, a plurality of guide-disks slidably mounted in sets on opposite sides of said frame for guiding

the edge portions of said strip fabric along a predetermined path, said textile fabric passing between said guide-disks, then rearwardly over said table, over said friction roller and being secured to said rewinding roller, said rotary cutters being keyed to said shaft and being pivotally mounted on said arms to swing on said drive shaft to and from said table and means for slidably mounting said cutters for adjustment in spaced relation from each other.

3. In a cloth cutting machine comprising rotary cutters adjustable for shearing textile fabric into strips of equal width and in one operation, a portable platform for supporting a bolt of fabric, a frame, a plurality of horizontally supported rods spaced apart and secured at opposite ends of said frame for engaging and smoothing said fabric, a table, a friction roller mounted at the rear of said table and having its upper surface in line with the top of said table, said roller having a felted friction surface adapted for feeding said fabric by frictional engagement, a drive shaft mounted above said table, arms slidably mounted on said drive shaft and having said rotary cutters supported at the free ends thereof, means operatively connecting said drive shaft and said rotary cutters and causing said cutters to be rotated by said drive shaft, a power-driven rewinding roller at the rear of said frame, sets of guide-disks slidably mounted on opposite sides of said frame for guiding both edge portions of said fabric along a predetermined path, said textile fabric passing between said guide-disks, then rearwardly over said table, over said friction roller and being secured to said rewinding roller, said rotary cutters and said cutter arms being pivoted on said drive shaft to swing to and from said table, and means for slidably mounting said cutters for adjusting the spacing from each other.

4. In a cloth cutting machine comprising a plurality of rotary cutters adjustable for shearing textile fabric having spaced linear dividing lines into strips of uniform widths and in one operation, a portable platform for supporting a bolt of fabric, a frame, a plurality of horizontally supported rods spaced apart and secured at opposite ends of said frame for engaging and smoothing said fabric, a table, a roller mounted at the rear of said table and having its upper surface in line with the top of said table, a drive shaft mounted above said table, arms slidably mounted on said drive shaft and having said rotary cutters supported at the free ends thereof, means operatively connecting said drive shaft and said rotary cutters and causing said cutters to be rotated by said drive shaft, a power-driven rewinding roller at the rear of said frame, means slidably mounted on opposite sides of said frame for guiding both edge portions of said fabric along a predetermined path, said textile fabric passing between said guide means, then rearwardly over said table, over said roller at the level of said table and being secured to said rewinding roller, said rotary cutters and said cutter arms being pivoted on said drive shaft to swing to and from said table, and means for slidably mounting said cutters for adjusting the spacing from each other, said plurality of rotary cutters being movable as a unit into alignment with said linear dividing lines.

DAVID E. VAN MALDEGHEM.
